Des. 235,055
Patented May 6, 1975

235,055

WATER DEPTH INDICATOR OR THE LIKE

Edward W. McCloskey, 271 Alpine St.,
Pasadena, Calif. 91106

Filed Mar. 29, 1973, Ser. No. 346,122

Term of patent 14 years

Int. Cl. D10—04

U.S. Cl. D10—101

Fig. 1

Fig. 2

Fig. 3

Fig. 4

Fig. 5

Fig. 6

FIG. 1 is a typical perspective view of a water depth indicator or the like showing my new design;

FIG. 2 is a side elevational view thereof with the upper portion broken away to illustrate the float therein;

FIG. 3 is a side elevational view thereof with the float in a raised position;

FIG. 4 is a side elevational view thereof with the cap disposed thereon;

FIG. 5 is a top plan view of FIG. 1; and

FIG. 6 is a bottom plan view thereof.

I claim:

The ornamental design for a water depth indicator or the like, as shown and described.
